UNITED STATES PATENT OFFICE.

FREDERICK G. WILSON, OF SYRACUSE, NEW YORK, ASSIGNOR TO JOSEPH SEYMOUR MANUFACTURING COMPANY, OF SYRACUSE, NEW YORK, A CORPORATION OF NEW YORK.

DESIGN FOR A HANDLE FOR SPOONS OR SIMILAR ARTICLES.

SPECIFICATION forming part of Design No. 35,821, dated March 18, 1902.

Application filed February 18, 1902. Serial No. 94,695. Term of patent 7 years.

To all whom it may concern:

Be it known that I, FREDERICK G. WILSON, a citizen of the United States, residing at Syracuse, in the county of Onondaga, State of New York, have invented and produced a new and original Design for a Handle for Spoons or Similar Articles, of which the following is a clear and exact specification, reference being had to the accompanying drawings, in which—

Figure 1 shows the obverse side of the handle, and Fig. 2 the reverse side, these two views being sufficient to illustrate my design, no claim being made upon anything else except the handle, which of course can be used upon knives, forks, or similar articles.

As shown in the drawings, the leading or material feature of my design consists in a handle for a spoon or similar articles which gradually increases in width from the stem to the outer end of the handle, the obverse side of the handle being plain, except that it is ornamented by the leaves and blossom of a poppy. The extreme end of the handle contains in relief-work the poppy-blossom, and just below it, extending transversely upon the handle, are the leaves. The reverse side of the handle shows the stems of the poppy, one extending from the lower end of the shank, serpentine in form, and terminating at the up-

per end in the poppy-blossom. Another stem extends from the central portion of the shank to the outer end of the handle and terminating in a smaller blossom, the stems thereby forming an oval-shape figure, as shown in Fig. 2, the whole forming a unique unitary article of manufacture.

Referring now to the drawings, *a* is the handle, *b* the blossom upon the outer end of the obverse side of the handle, and *c* the leaves.

d is the poppy-stem upon the reverse side of the handle, terminating in a small bulb *d'* at the lower end and in a large blossom *e* at the upper end. *f* is the shorter stem of the poppy, said stems *d* and *f* so resting upon the obverse side of the handle as to form an oval-shape figure.

Having thus described my invention, what I claim, and desire to secure by Letters Patent, is—

The design for a handle for spoons, or similar articles, as herein described and shown.

In witness whereof I have hereunto set my hand this 5th of February, 1902.

FRED. G. WILSON.
